UNITED STATES PATENT OFFICE.

THOMAS W. MILLER, OF ASHLAND, OHIO, ASSIGNOR TO THE FAULTLESS RUBBER COMPANY, OF ASHLAND, OHIO, A CORPORATION OF OHIO.

REED FOR TOYS.

1,146,640.

Specification of Letters Patent.

Patented July 13, 1915.

Application filed April 30, 1915. Serial No. 24,996.

To all whom it may concern:

Be it known that I, THOMAS W. MILLER, a citizen of the United States, residing at Ashland, in the county of Ashland and 5 State of Ohio, have invented certain new and useful Improvements in Reeds for Toys, of which the following is a specification.

My invention relates to reeds, more particularly for toys, such as sounding toy balloons, and has for its object to provide a construction which may be disposed in position for use, and will there remain without the necessity for any attaching or retaining means, thus obviating the necessity 15 for skilled labor in assembling these articles.

In the accompanying drawing:—Figure 1 is a side elevation of a tube having my improved reed applied thereto, a toy balloon also being shown in section applied thereto. 20 Fig. 2 is a detail perspective view of that end of the tube of Fig. 1 to which my improved reed is applied. Fig. 3 is an enlarged detail perspective view of one form 25 of my improved reed. Fig. 4 is a similar view partly broken away of another form of said reed. Fig. 5 is a sectional view indicating my improved reed applied to a slightly modified construction.

Similar numerals of reference denote corresponding parts in the several views.

In Figs. 1 and 2, the reference numeral 1 denotes a tube of any suitable construction, usually formed of wood. My improved reed, which is formed of rubber, preferably 35 is formed initially in cap shape, comprising a cylindrical portion 2 and a top diaphragm, which in Figs. 1, 2 and 3 is shown cutaway at each side at 3 to leave the central strip 4 adapted to vibrate under the passage of air 40 to produce the desired sound. In applying my improved reed, it is necessary only that the tubular portion 2 of the same be slipped over the enlarged end of the tube 1, and the same thereby will be retained firmly in 45 place. When used in connection with a toy balloon, the latter shown at 5 then may be slipped over the end of the tube 1, whereupon the device is ready for use. In Fig. 4,

I have shown a slightly modified construction of my improved reed, the vibrating portion 6 thereof being formed by slitting the diaphragm, instead of cutting the same away as in Fig. 3. It is understood that heretofore these vibrating members or reeds, which are stretched transversely across the 55 end of a tube, have been fastened in position by tying or by other extraneous means, which necessitates the employment both of time and skill in the labor, thereby materially increasing the cost. My improved 60 construction of reed is adapted to be placed on the tube 1 or other similar position by unskilled labor and without employing any fastening means. In Figs. 5, I have shown my improved reed, which is indicated at 7, 65 applied to an apertured spool 8 preferably of wood, said spool having applied thereto exterior to the reed 7 a rubber tube 9, and over both of these the mouth of a toy balloon 10, this construction providing an extremely 70 inexpensive, and yet thoroughly efficient device.

While I have shown and described my reed as particularly adapted for sounding toy balloons, I do not wish to be understood 75 to limit the same to such use, as it is equally well adapted for use as a reed for any form of musical instrument or toy.

Having thus described my invention, what I claim as new and desire to secure by Letters Patent, is:—

1. A reed, comprising a tubular sleeve of rubber and a cap integral with said sleeve and slitted to provide a vibrating portion, said vibrating portion adapted to span the 85 space in the reed receiving member through which the air is forced.

2. A reed comprising a tubular sleeve of rubber and a cap integral with said sleeve and closing one end thereof, said cap being 90 cut to form a vibrating portion extending from one side to the other of said sleeve.

In testimony whereof I have hereunto set my hand this 27th day of April, 1915.

THOMAS W. MILLER.
